UNITED STATES PATENT OFFICE.

PHILIP L. HOWE, OF BREEZY HILL, KANSAS.

INTERNAL-COMBUSTION ENGINE.

1,228,923.

Specification of Letters Patent.

Patented June 5, 1917.

Application filed May 3, 1916. Serial No. 95,047.

To all whom it may concern:

Be it known that I, PHILIP L. HOWE, a citizen of the United States of America, residing at Breezy Hill, in the county of Crawford and State of Kansas, have invented new and useful Improvements in Internal-Combustion Engines, of which the following is a specification.

The present invention relates to improvements in internal combustion engines and particularly to the construction of manifolds in connection with the charge forming and exhaust devices of the engine. In general, the invention is devised for the purpose of utilizing the heat from the exhaust of the engine to vaporize or gasify kerosene or other hydro-carbons of high specific gravity so that the use of such hydrocarbons is practicable in internal combustion engines.

20 In particular the object of the invention is to provide a device or manifold through which the exhaust gases of combustion pass, which will vaporize the charge of fuel as it is passing to the engines, and maintain the 25 charge in gaseous or vaporized form until the charge passes into the predetermined cylinders of the engine.

By the utilization of my invention I am 30 enabled to heat and vaporize the fuel charge so that the fuel gas delivered to the different cylinders is of a uniform temperature, thus insuring uniform combustion in the cylinders, and furthermore, the use of my invention eliminates the possibility of the charge 35 of gaseous fuel condensing after once being vaporized, as the heat from the exhaust gases is at all times continuously and uniformly applied to the gaseous fuel charge until it passes to the cylinder of the engine.

40 The invention consists essentially in certain novel combinations and arrangements of parts of the exhaust and intake manifolds as will be more fully specified hereinafter.

In the accompanying drawings I have 45 illustrated one complete example of the physical embodiment of my invention constructed according to the best mode I have so far devised for the practical application of the principles of my invention, but it will 50 of course be understood that I contemplate making changes in details of construction without departing from the spirit of my invention.

Figure 1 is a side elevation of a well 55 known type of automobile engine or motor with my invention embodied therein.

Fig. 2 is a longitudinal horizontal sectional view illustrating the ports or connections of the manifolds of the intake and exhaust to the engine.

Fig. 3 is an enlarged, partly sectional view, as seen from the rear of the engine, of the combined manifold.

Fig. 4 is a vertical transverse view of the horizontal branch of the manifolds, showing the manner of attaching the manifolds to the engine casing.

Fig. 5 is a horizontal view of the manifolds on line 5—5 of Fig. 3.

In illustrating the preferred embodiment 70 of my invention I have utilized a well known make of internal combustion engine as 1, of the four cylinder type and displaced the two customary manifolds with a single hollow integral casting of which the outer 75 shell or exhaust casing is fashioned with a pair of oppositely extending horizontal arms 2 and 3 and a downwardly projecting leg 4 which is shown as disposed obliquely to the two arms, but of course any suitable angle 80 may be used in arranging the leg, and the lower end of the casing is formed with a backward turned branch 5, which is open as shown for exhaust gases of combustion to pass therefrom in usual manner. In Fig. 2 85 it will be seen that there are four ports as 6, 7, 8, 9 connected to the engine 1 adapted to exhaust the gas of combustion into the upper portion of the exhaust manifold and the currents of gases from all of the ports 90 are brought in uniform quantities toward the center of this portion of the casing and all the currents passed down through the leg 4 of the manifold. In this manner approximately one-half of the gases of combustion 95 from the engine pass through each arm of the horizontal portion of the exhaust manifold, and the entire exhaust is brought down through the leg of the casing and out at its bent end, uniformly heating the fuel charge 100 within the intake.

Within the casing or exhaust manifold a second and smaller manifold is inclosed, which is the intake manifold for fuel gases. This manifold, as before stated, is integral 105 with the outer casing, and is fashioned with two horizontally disposed branches 10 and 11, which enter the engine by means of the ports 12 and 13 respectively, and it will be seen that these branches are symmetrically 110 arranged within the exhaust manifold and provided with an obliquely projecting leg

14, which terminates in the exterior tubular boss 15 projecting to the rear and parallel with the bent end 5 of the manifold.

By means of the integral flanges 16 of 5 the boss, and suitable stud bolts as 17, the carbureter 18 is attached to the boss and it has free communication from its interior with the intake manifold at one side while at the other side an air pipe 19 is connected 10 which receives air from the open funnel or mouth end 20. It will be noted that the funnel end of this air pipe partly surrounds the rear end of the exhaust manifold so that the air which enters the funnel and is conveyed to the carbureter is heated to a desirable degree. The usual throttle or air valve 21 is provided, for priming, and is located in the boss 15 and controlled by the wire or rod 22 which extends to the radiator 15 of the engine usually located at the front.

A suitable supply of moisture in the shape of steam or water is supplied to the intake manifold through pipe 23, and controlled as 25 customary from the driver's seat by the needle valve indicated at 24 and wire or rod 24' (Fig. 2). The pipe 23 is connected to the boss 25 which is cast integral with the legs of the exhaust and intake manifolds and the boss opens in to the leg 14 of the intake. Located preferably below the steam or water inlet is a gasoline pipe 26 which is employed to furnish fuel for the initial operations of the engine, before 30 the heavier kerosene is used. The flow of gasoline is fixed by the needle valve indicated at 27 and the supply is regulated by the needle valve 28, the latter controlled from the driver's seat of the car. A hollow 35 integral boss 25' is employed as the connection between the gasoline inlet pipe 26 and the intake and vaporized gasoline is drawn into the cylinder from the intake as usual.

The integral manifolds are attached to 40 the engine casing by means of a suitable number of U-bolts 29, and yokes 30, the former surrounding the horizontal arms of the manifold, and the latter clamped to the bolts by nuts 31. A stud bolt 32 is used 45 to attach the yoke to the casing as shown in Fig. 4, and unions or couplings 33 are used to attach the port pipes to the casing, as seen in Fig. 3.

It is very necessary that the gasoline mixture must have the same temperature and expansion for each cylinder of the motor, otherwise imperfect action of engine will result. With an unequal expansion of the gas mixture for the several cylinders it is 50 impossible to make a practical adjustment of the carbureter.

My device is so constructed that it completely, effectually and evenly vaporizes the

kerosene, and keeps it in this desirable and necessary condition until it is admitted into the engine. My device uniformly heats and expands the gaseous mixture.

It is plainly seen that in order to uniformly and evenly heat, vaporize and expand the gaseous mixture for fuel to each 70 and every cylinder, the exhaust from all of the cylinders must be brought to a point midway between the ends of manifolds and then discharged downward around the angular leg of the intake to where the intake 75 makes its point of exit, whence the exhaust continues through the discharge to outside air.

What I claim is:

1. The combination with an internal combustion engine, of an outer manifold, said outer manifold having oppositely extending arms with exhaust ports connected to the engine and an angularly disposed leg with an open end, and an inner manifold forming 85 the intake and having branches in said arms connected by ports to the engine, a leg to the intake manifold within the exhaust manifold leg, said leg having an exterior hollow boss in which the intake leg terminates, 90 and a carbureter attached to said boss.

2. In a device of the character described, the combination with an explosive engine, of a horizontally disposed exhaust manifold secured thereon, an exhaust pipe extending 95 downwardly from said exhaust manifold, an intake manifold positioned in spaced relation within said exhaust manifold, an intake pipe for said intake manifold projecting downwardly for a distance centrally 100 within said exhaust pipe, and projecting laterally through one side wall thereof, means for supplying gasoline to said intake pipe, means for supplying carbureted kerosene to said laterally extending intake pipe, means for injecting a stream of water into 105 said intake pipe, and means for independently controlling the gasoline, the carbureted kerosene, and the water, for regulating the character of the explosive mixture.

3. A manifold for explosive engines comprising an exhaust manifold, an exhaust pipe extending downwardly from the exhaust manifold, said exhaust pipe terminating in a horizontally disposed extension, an 115 intake manifold disposed centrally within the exhaust manifold, and an intake pipe extending downwardly from the intake manifold and centrally within the exhaust pipe, said intake pipe projecting laterally 120 through the wall of the exhaust pipe at a point intermediate the exhaust manifold and the exhaust pipe extension.

In testimony whereof I affix my signature.

PHILIP L. HOWE.
